LOCK SHINGLE

Martin G. O'Reilly, Chicago, Ill., assignor to Ford
Roofing Products Company, Chicago, Ill., a cor-
poration of Illinois

Application January 19, 1946, Serial No. 642,302

2 Claims. (Cl. 108—7)

1

This invention relates to so-called lock shingles.

Lock shingles are generally made from flexible material called prepared roofing and are of such design as to provide formations adapted to interlock with adjacent shingles to assist in holding the exposed lower portion of the shingle against curling or flexure. It is thus possible to effect economies by making the shingle much larger than would be possible with material of this flexibility without increasing the danger to leakage which would otherwise be present owing to the ease with which flexible material of this character can be bent up by wind during storms unless the lower edge thereof be fastened down. The interlocking elements if efficient generally result in a shingle of complex contour which results in an unconventional or unpleasing shingle pattern on the roof. Moreover it is difficult to cut shingles of this character from the sheet roofing material without waste. Production of waste is objectionable not so much because of loss due to waste material but to the impossibility of preventing pieces of waste from lodging between the shingles in a package and therefore discoloring or marring the surface of the shingle.

Among other objects the invention aims to provide an efficient and improved lock shingle which presents a regular or conventional shingle pattern in the roof and yet which may be cut without waste. Heretofore lock shingles which have presented a regular, e. g. rectangular shingle outline, have involved the use of an excessive amount of roofing material, and the exposed shingle pattern has been limited or determined by the design or dimensions of the locking elements.

Another object of the invention is to provide a shingle of this character which may be nailed or fastened to the roof closely adjacent the bottom of the exposed shingle tab without exposing the nail.

The nature of the invention may be readily understood by reference to one illustrative shingle and its method of manufacture shown in the accompanying drawing.

In said drawing:

Fig. 1 is a plan view of the illustrative shingle;

Fig. 2 is a diagram illustrating the manner of cutting the shingles without waste from a sheet of roofing material. The diagram illustrates a sheet of roofing material having a width corresponding to the depth of only one shingle but it will be understood that in practice the roofing sheet is wide enough to provide a plurality of rows of shingles thus cut; and

2

Fig. 3 is a plan view of a portion of a roof surface covered by a plurality of courses of interlocked shingles of the type illustrated in Fig. 1.

The illustrative shingle which may be preferably cut from so-called prepared roofing which is flexible in character, comprises a rectangular exposurer body portion 10 having straight and parallel upper and lower edges 11 and 12. Projecting from each side edge are head tabs 13 whose combined width preferably equals the width of the body portion 10. Below the head tabs and projecting from an intermediate middle portion of the body are nailing tabs 14 adapted to receive nails for attaching the shingle. The nailing tabs are preferably made substantially wide at their lower portions 15 so as to allow substantial latitude in the placing of a nail. Often, owing to the character of the surface over which the shingles are applied, it is impossible for the workman to place the nail at the same point in each tab. It is necessary to shift the nail to a point over a firm spot underneath the tab. The wide lower portion is provided on the nailing tab by cutting the side edge 15a of the tabs so as to diverge outwardly toward the lower edge of the tab. The latter is provided with a locking notch 16 which preferably aligns with the imaginary side edge 17 of the body portion. The notch is formed simply by slitting the roofing material and preferably not removing any material which may become lodged between shingles in a bundle. The notch is adapted to interlock with an adjacent shingle as next described.

Projecting from the lower portion of the shingle and preferably in line with the lower edge thereof are locking tabs 18 adapted to seat in the notches 16 of adjacent shingles. The locking tab 18 is here shown of the same depth as the notch 16 so that when the shingles of one course are interlocked with the shingles of the next lower course, the lower edge 12 will register with the edges 15 of the nailing tabs of the next lower course. By reference to Fig. 2 it will be observed that the contour of the side edge of a shingle is complementary with that of another shingle in reversed position. Thus the material for forming the wide lower portion of the nailing tab is provided by narrowing the upper portion 19 of the nailing tab of the complementary shingle. The locking tabs 18 of each shingle are complementary with notches cut in the concealed upper corners of the head tabs 13 of the complementary shingle.

In the illustrative shingle the head tabs and nailing tabs each occupy one-third of the height

of the shingle. A satisfactory shingle of this character may be 24" in height and 24" in width at the head tabs, thus providing an exposed shingle area of 12" in width and 16" in height. This area though large in relation to the total area of the shingle, nevertheless provides adequate protection against leakage since all portions are safely anchored.

As illustrated in Fig. 3 in laying the shingles the head tabs 13 of each course are abutted and aligned. Thus each course comprises a series of body portions 10 separated by spaces of a width equal to that of the body portion. The next overlying course is staggered so that the body portions of the shingles of that course register with the spaces between the shingles of the course below.

As each course is laid the shingles are nailed by driving nails 21 through the nailing tabs 14 wherever the workman finds a firm spot underneath the tab. Preferably the nails should be located fairly close to the lower edge of the tabs since the interlock with the adjoining shingle occurs at this point. After thus nailing a course of shingles the next course is applied by inserting each locking tab 18 in a notch 16 of the lower course so that the tabs underly the body of the shingle in the said lower course and the body of the shingle overlies the spaces between the shingle bodies and conceals the locking tabs 14 of the said lower course. The lower edge 12 of the shingles of one course aligns with the lower edges 15 of the underlying nailing tabs, thus providing an exposed double thickness of roofing at the lower edge of the shingle to provide a heavy shadow line which improves the appearance or texture of the roof. If desired, the locking tabs 18 may be partly notched at a point in alignment with notch 16. In that event the notch 16 is made shorter. The combined depth of the notches should equal the depth of the locking tab 18 so that the lower edge of the shingle 12 will register with the edge 15 of the underlying nailing tab.

Successive courses of shingles are thus laid, the shingles of one course being staggered relative to those of the next lower course. The resultant shingle outline or pattern is a very desirable one, namely that provided by a series of plain staggered rectangles whose depth is two-thirds of the total depth of the shingle. While the side edges of the exposed rectangular areas are in alignment with those of the next lower course it will be noted that at all points sufficient side underlap is provided to prevent leakage. The minimum underlap occurs at the top 19 of each nailing tab but at this point a third thickness of roofing, that comprising the head tab 13 of the underlying shingle of the second lower course, registers with the nailing tab.

Despite the substantial width of the shingles, the lower edge 12 of each shingle is firmly fastened at its corners by the locking tabs 18 which are in turn held down by the closely adjacent underlying nail which passes through the locking tab 14 at a point closely adjacent the point of interlock. Without sacrifice in protection at points where it is required and without modification of the rectangular shingle pattern, it is possible by tapering the nailing tabs as shown to provide a substantial area for receiving a nail at a point closely adjacent the locked corner of the lower edge of the overlying course of shingles. The workman may thus locate the nail at a firm

spot on the underlying supporting surface. This is important because shingles of this character are often laid over old shingled surfaces which because of their irregularity do not provide points of uniform firmness to which the shingles may be nailed. If a nail be driven at a soft or hollow spot the shingle is very often broken when driving in the nail. With the present shingle the lower portion of the nailing tab is of sufficient area to make it possible to locate the nail at a firm spot and thereby to avoid breakage of the shingle in nailing.

Obviously the invention is not limited to the details of the illustrative shingle or its method of manufacture since these may be variously modified. Moreover it is not indispensable that all features of the invention be used conjointly since various features may be used to advantage in different combinations and sub-combinations.

Having described my invention, I claim:

1. A lock shingle comprising in combination a rectangular body portion having straight top and bottom edges and having projecting from each side edge a head tab, an intermediate nailing tab, and a locking tab at the bottom edge of the shingle, the inner ends of said intermediate and locking tabs being in alignment with the adjacent side edge of said body portion, the contour of each side of the shingle being complementary with that of another like shingle in reversed position so that said shingles may be cut from roofing material without waste, said nailing tabs having their outer side edges diverging downwardly to increase the area of each nailing tab adjacent its lower edge without increasing the total area of the nailing tab, notch means for interlocking the locking tab of an adjacent shingle with a nailing tab in line with a side edge of said rectangular body, thereby to expose only said rectangular body portion, the wider lower portions of said nailing tabs providing substantial nailing areas closely adjacent said interlocking means.

2. A lock shingle comprising in combination a rectangular exposed body portion having nailing tabs projecting from its opposite side edges intermediate the top and bottom edges thereof and having locking tabs projecting from said opposite side edges adjacent said bottom edges, said nailing tabs being tapered by having their side edges diverging toward said bottom edge so that the nailing tabs are substantially wider at their bottoms than at their tops, notch means adjacent the wider lower ends of said nailing tabs and in alignment with the side edges of said rectangular body portion for forming an interlocking connection with a locking tab of an adjacent shingle which overlies said nailing tab, the wider lower portions of said nailing tabs providing substantial areas adjacent the interlocking connections to receive fastening nails.
